SEALED FILLING CAP FOR FUEL STORAGE TANKS

Abraham A. Arvintz and Nathan A. Arvins, Brooklyn, and Robert A. Arvintz, New York, N. Y., assignors to Sanicom Company, Inc., Brooklyn, N. Y., a corporation of New York

Application August 25, 1950, Serial No. 181,544

9 Claims. (Cl. 210—166)

1

This invention relates to filling caps usually countersunk into a pavement of a filling station or the like for use in transferring fuel from a supply vehicle to tanks submerged in the ground under the pavement. More particularly, the invention deals with a filling cap of the character described having means for quickly removing the cover plate and to incorporate on the plate a seal valve member to provide a dual seal or closure substantially eliminating entrance of water into the filter chamber of the device.

The novel features of the invention will be best understood from the following description, when taken together with the accompanying drawing, which drawing is a sectional view through a filling cap device made according to our invention.

In the drawing, 1 represents the casing of the device which is embedded into a pavement or other supporting surface 2, so that the outer peripheral edge 3 of the casing is flush with the pavement. The casing has a large lower filter chamber 4, with a side outlet 5, with which a pipe couples for transferring filtered fuel to the receiving tank, not shown.

Above the chamber 4, the casing has an enlarged inlet chamber 6, sub-divided from the chamber 4 by an inwardly extending annular flange portion 7, to which is secured the outwardly extending flange 8 of a valve casing 9. The primary casing 1 has a passage 10 communicating with the chamber 6 for venting said chamber and for drainage, if desired.

The valve casing 9 has a lower bevelled valve seat 11, upon which a tapered disc valve 12 is adapted to seat. The valve 12 carries a spaced annular ring 13, spaced from the valve by a series of opposed webs 14, two opposed webs 14 having vertical apertures 15, in which guide pins 16 secured to the casing 9 operate. The pins 16 also check inward movement of the valve 12. The bore of the valve casing 9 is threaded, as seen at 17, to receive a suitable fitting on the end of a supply pipe so that, when the filling cap is open, as later described, this coupling, as it is screwed into the casing 9, moves the valve 12 down into opened position, as indicated in dot and dash lines. The valve 12 has a depending stem 18 which operates in a raised bearing 19 on the bottom of the casing 1 and against a spring 20 disposed in said bearing. The spring 20 is tensioned to normally maintain the valve 12 in seated position.

At 21 is shown a closure plate which seats in a groove portion 22 of the casing 1, as shown. The

plate 21 has, centrally thereof, a socket 23 for the reception of a suitable wrench. Below the socket 23 is a bearing 24 in which a pin 25 is slidably and rotatably mounted. The pin 25 has a long annular recessed portion 26 engaged by one or more screws 27 to retain the pin 25 against displacement from the bearing 24, while permitting free rotary and sliding movement therein. The lower end of the pin 25 carries a supplemental seal or valve plate 28 which seats upon the upper surface of the valve casing 9, as seen at 29, so as to effect a seal between the chamber 6 and the interior of the casing 9 above the valve 12. This provides a dual seal controlling communications between the chamber 6 and the chamber 4.

At one side of the closure plate 21 is a bayonet slot enlargement 30, part of the slot of which is indicated at 31. This slot is adapted to engage a pin 32 in the casing 1 to draw the plate 21 into sealed position, thus effecting a primary seal to the casing 6.

Seating snugly in the bore 7' of the flange 7 is the upper ring portion 33 of a cup-shaped strainer 34 disposed in the chamber 4 in spaced relation to the walls of the casing 1 in the manner illustrated. The bottom of the strainer 34 has an upwardly pressed member 35 terminating in a ring opening 36 to fit snugly, but freely, around the valve stem 18. The ring 36 is adapted to seat upon the bearing 19, thus positioning the strainer within the casing. With this construction, it will appear that a large strainer area is provided for efficient operation of the device without danger of retarding flow of the fuel outwardly through the discharge 5.

From time to time, the casing 9 can be removed for cleaning the strainer or for replacement of the strainer, whenever desired. It will be understood from the foregoing that, when the cap 21 is removed, the seal or valve plate 28 is removed with the cap, thus immediately giving access to the threaded bore of the valve casing 9.

A spring 37 is provided between the bottom of the seal or valve plate 28 and the bearing 24 to tensionally seat the member 28 as and when the plate 21 is in position. For this reason, movement of the pin 25 in the bearing 24 is provided.

Having fully described our invention, what we claim as new and desire to secure by Letters Patent is:

1. A filling device of the class described, comprising a casing partitioned to form an upper inlet chamber and a lower strainer chamber, a de-

tachable cover plate controlling admission to the inlet chamber, the lower part of the casing having an outlet for discharge of fluid passed through the device, a valve casing and a valve forming the partition between said chambers, tensional means for normally seating the valve on the valve casing to close communication between said chambers, a valve plate yieldably supported on the cover plate and yieldably engaging the valve casing to form a secondary seal between said chambers, a large cup-shaped strainer supported in the casing and arranged within the strainer chamber in spaced relation to the side and bottom walls thereof, the lower part of the casing having a bearing portion extending into the casing, the valve having a stem operating in said bearing portion, and a spring in the bearing portion engaging the stem to support the valve in seated position.

2. A filling device of the class described, comprising a casing partitioned to form an upper inlet chamber and a lower strainer chamber, a detachable cover plate controlling admission to the inlet chamber, the lower part of the casing having an outlet for discharge of fluid passed through the device, a valve casing and a valve forming the partition between said chambers, tensional means for normally seating the valve on the valve casing to close communication between said chambers, a valve plate yieldably supported on the cover plate and yieldably engaging the valve casing to form a secondary seal between said chambers, a large cup-shaped strainer supported in the casing and arranged within the strainer chamber in spaced relation to the side and bottom walls thereof, the lower part of the casing having a bearing portion extending into the casing, the valve having a stem operating in said bearing portion, a spring in the bearing portion engaging the stem to support the valve in seated position, and the bottom of the strainer having a raised portion seating on said bearing.

3. A filling device of the class described, comprising a casing partitioned to form an upper inlet chamber and a lower strainer chamber, a detachable cover plate controlling admission to the inlet chamber, the lower part of the casing having an outlet for discharge of fluid passed through the device, a valve casing and a valve forming the partition between said chambers, tensional means for normally seating the valve on the valve casing to close communication between said chambers, a valve plate yieldably supported on the cover plate and yieldably engaging the valve casing to form a secondary seal between said chambers, a large cup-shaped strainer supported in the casing and arranged within the strainer chamber in spaced relation to the side and bottom walls thereof, the lower part of the casing having a bearing portion extending into the casing, the valve having a stem operating in said bearing portion, a spring in the bearing portion engaging the stem to support the valve in seated position, the bottom of the strainer having a raised portion seating on said bearing, the partition portion of the casing being partially formed by an inwardly extending annular flange, and the upper end of the strainer having a ring seating in said flange.

4. A device of the character described, comprising a substantially cup-shaped main casing, the casing having, intermediate its ends, an inwardly projecting annular flange partially partitioning the casing to form an upper inlet chamber and a lower strainer chamber, a valve casing mounted on said flange and extending into the lower chamber, said valve casing having a tubu-

lar portion with a valve seat at its lower end, the upper end of the tubular portion being internally threaded, a valve, said valve having a stem operating in a bearing in the bottom of the main casing, a spring in said bearing engaging the stem to normally support the valve on said valve seat, said valve having a ring normally arranged within the upper threaded portion of the valve casing and spaced from the valve by a plurality of webs, means on the valve casing engaging webs of the valve for keying the valve against rotation, a cover plate detachably coupled with the upper end of the main casing for closing the inlet chamber, and a valve plate yieldably and movably supported on the closure plate and operatively engaging the valve casing to form a secondary seal between the upper and lower chambers of the main casing.

5. A device of the character described, comprising a substantially cup-shaped main casing, the casing having, intermediate its ends, an inwardly projecting annular flange partially partitioning the casing to form an upper inlet chamber and a lower strainer chamber, a valve casing mounted on said flange and extending into the lower chamber, said valve casing having a tubular portion with a valve seat at its lower end, the upper end of the tubular portion being internally threaded, a valve, said valve having a stem operating in a bearing in the bottom of the main casing, a spring in said bearing engaging the stem to normally support the valve on said valve seat, said valve having a ring normally arranged within the upper threaded portion of the valve casing and spaced from the valve by a plurality of webs, means on the valve casing engaging webs of the valve for keying the valve against rotation, a cover plate detachably coupled with the upper end of the main casing for closing the inlet chamber, a valve plate yieldably and movably supported on the closure plate and operatively engaging the valve casing to form a secondary seal between the upper and lower chambers of the main casing.

6. A device of the character described, comprising a substantially cup-shaped main casing, the casing having, intermediate its ends, an inwardly projecting annular flange partially partitioning the casing to form an upper inlet chamber and a lower strainer chamber, a valve casing mounted on said flange and extending into the lower chamber, said valve casing having a tubular portion with a valve seat at its lower end, the upper end of the tubular portion being internally threaded, a valve, said valve having a stem operating in a bearing in the bottom of the main casing, a spring in said bearing engaging the stem to normally support the valve on said valve seat, said valve having a ring normally arranged within the upper threaded portion of the valve casing and spaced from the valve by a plurality of webs, means on the valve casing engaging webs of the valve for keying the valve against rotation, a cover plate detachably coupled with the upper end of the main casing for closing the inlet chamber, a valve plate yieldably and movably supported on the closure plate and operatively engaging the valve casing to form a secondary seal between the upper and lower chambers of the main casing, means retaining the valve plate against displacement from said closure plate.

the strainer having a part fitting snugly within the annular flange of said casing.

7. A device of the character described, comprising a substantially cup-shaped main casing, the casing having, intermediate its ends, an inwardly projecting annular flange partially partitioning the casing to form an upper inlet chamber and a lower strainer chamber, a valve casing mounted on said flange and extending into the lower chamber, said valve casing having a tubular portion with a valve seat at its lower end, the upper end of the tubular portion being internally threaded, a valve, said valve having a stem operating in a bearing in the bottom of the main casing, a spring in said bearing engaging the stem to normally support the valve on said valve seat, said valve having a ring normally arranged within the upper threaded portion of the valve casing and spaced from the valve by a plurality of webs, means on the valve casing engaging webs of the valve for keying the valve against rotation, a cover plate detachably coupled with the upper end of the main casing for closing the inlet chamber, a valve plate yieldably and movably supported on the closure plate and operatively engaging the valve casing to form a secondary seal between the upper and lower chambers of the main casing, means retaining the valve plate against displacement from said closure plate, a cup-shaped strainer arranged in the strainer chamber, said strainer seating on and partially encircling said bearing, the upper end of the strainer having a part fitting snugly within the annular flange of said casing, and the casing having threaded apertures communicating with the chambers thereof.

8. A filling device of the class described, comprising a casing partitioned to form an upper inlet chamber and a lower strainer chamber, a detachable cover plate controlling admission to the inlet chamber, the lower part of the casing having an outlet for discharge of fluid passed through the device, a valve casing and a valve forming the partition between said chambers, tensional means for normally seating the valve on the valve casing to close communication be-

tween said chambers, said cover plate having a central bearing projecting into said inlet chamber, a valve plate having a projecting pin slidably mounted in said bearing, means on the bearing checking movement of the pin in both directions, means between said bearing and valve plate for yieldably supporting the cover plate in engagement with the valve casing to form a secondary seal between said chambers, and a large cup-shaped strainer supported in the casing and arranged within the strainer chamber in spaced relation to the side and bottom walls thereof.

9. In filling devices of the character described, comprising a casing having an upper inlet chamber and a lower strainer chamber, means comprising a valve closing communication between said chambers, a cover plate detachably coupled with the casing controlling admission to said inlet chamber, said plate having a central bearing projecting into said inlet chamber, a valve plate having a projecting pin slidably mounted in said bearing, means on the bearing checking movement of the pin in both directions and retaining the valve plate in coupled relation with said cover plate, a coil spring on said pin between the bearing and valve plate, said spring being adapted to tensionally support the valve plate in engagement with the first named means in forming a secondary seal between the inlet and strainer chambers, the lower portion of the casing having a discharge communicating with said strainer chamber, and the side wall of the upper portion of the casing having a vent communicating with the inlet chamber.
